UNITED STATES PATENT OFFICE.

JOHN G. MAGIN, OF ROCHESTER, NEW YORK, ASSIGNOR TO HENRY CONOLLY COMPANY, OF ROCHESTER, NEW YORK, A CORPORATION OF NEW YORK.

LOOSE-LEAF BINDER.

1,112,222.

Specification of Letters Patent. Patented Sept. 29, 1914.

Application filed October 30, 1912. Serial No. 728,655.

To all whom it may concern:

Be it known that I, JOHN G. MAGIN, of Rochester, in the county of Monroe and State of New York, have invented a new and useful Improvement in Loose-Leaf Binders, which improvement is fully set forth in the following specification and shown in the accompanying drawings.

The present invention relates to loose leaf binders and more particularly to that type having a removable transfer member on which certain of the leaves are held for the purpose of fitting other leaves to or removing them from the impaling posts or projections, and an object of this invention is to provide a construction in which an impaling projection and a transfer projection fit within a single opening of each leaf, the projections on the two parts being of such a construction that they are inexpensive to manufacture and coöperate with each other in such a manner that they are not liable to get out of order.

To these and other ends the invention consists in certain parts and combinations of parts all of which will be hereinafter described, the novel features being pointed out in the appended claims.

In the drawings: Figure 1 is a perspective view of a loose leaf binder constructed in accordance with this invention; Fig. 2 is a section through the supporting member, the transfer member and the retaining member while these parts are interlocked; Fig. 3 shows the transfer member and the supporting member in section and in slightly separated relation; Fig. 4 is a detail sectional view through one of the impaling and one of the transfer projections while these parts are associated; Fig. 5 is a detail view of the supporting member showing the impaling projection in cross section and the pocket at the base of the impaling projection; Fig. 6 is an enlarged detail view of a portion of a leaf showing one of the post openings; and Fig. 7 is a detail view showing an opening in the transfer member through which an impaling projection passes.

In the illustrated embodiment of the invention, the binder is in book form, one cover 2 of the book carrying a supporting member and the other cover 8 carrying a retaining member. The supporting member is preferably in the form of a bar 1 inclosed within the cover 2 and having posts or pro-

jections extending laterally therefrom in parallel relation. One longitudinal face 3 of each of these posts is preferably curved while the opposite longitudinal face 4 is flat so that the post is semicylindrical or has 60 a cross section of a half of a circle. Like longitudinal faces of these posts or projections are opposed, that is, in the present instance, the curved faces on the two projections are next to each other while the flat 65 faces 4 are nearer the ends of the supporting member 1. With this arrangement, when the leaves or sheets 5, with circular openings 6 therein, are fitted to these impaling projections or posts, the curved faces of the 70 posts or projections will engage the proximate sides of the openings 1 and prevent the lateral shifting of the leaves or sheets 5 on the impaling projections, while, at the same time, space will be provided on the outer 75 sides of the posts for the reception of transfer projections.

The transfer projections are at least two in number and extend laterally in parallel relation from the transfer member or bar 80 7. The transfer projections are also formed, in this embodiment, with curved longitudinal faces 8 and flat longitudinal faces 9, the flat faces of the transfer projections being, in this instance, opposed so that the curved 85 faces are on the outside or toward the ends of the transfer member. The distance between the transfer projections is greater than the distance between the impaling projections. In fact, the distance between the 90 outer flat faces of the impaling projections corresponds substantially to the distance between the inner flat faces of the transfer projections so that the transfer projections may fit snugly within the openings 6 of the 95 sheets at one time with the impaling projections, the ends of the transfer projections resting in notches 10 in the supporting member 1 at the bases of the impaling projections, and the latter projecting through 100 semicircular openings 10 in the transfer member 7 at the bases of the transfer projections. When so arranged, each impaling projection and its coöoperating transfer projection forms a cylinder whose diameter corresponds with the diameter of the opening in the loose leaf or sheet. It is apparent that the leaves or sheets will be held against movement on the transfer because the outer curved faces of the transfer members will 110

engage the outer sides of the two openings in the loose leaves or sheets.

Any suitable means may be employed for holding the transfer member and the supporting member in coöperative relation. Preferably, there is employed a retaining member comprising a tubular casing 12 having a sliding locking bar or latch 13 movable longitudinally therein, and pressed in one direction by a spring 14, movement in the other direction being effected by manipulating the projecting end 15 of the bar or latch. In order that the latch may co-operate with the impaling projections, the latter may be provided with shoulders 16 near their upper ends for engagement by the latch or bar 13, the casing 12 being perforated at 17 to permit the entrance of the upper ends of the impaling projections.

In the operation of the invention, assuming the parts to be in the positions shown in Fig. 2 and it is desired to remove a leaf or sheet, the projecting end 15 of the latch 13 is pressed inwardly to disengage such latch from the shoulders 16 when the binder cover 18 may be thrown backward to the position shown in Fig. 1. The transfer member 7, with a number of leaves or sheets 5, is raised as shown in Fig. 3, after which the desired leaf may be removed without disturbing the position of the leaves on the impaling projections on the supporting member.

A loose leaf binder constructed in accordance with this invention requires but two openings in the loose leaves. The transfer projection and the impaling projection may be made from the same stock and when co-operating form a cylinder which will fit within a circular opening. The flat co-operating faces on the impaling projections and the transfer projections do not require any expensive tools to form them and they are not liable to get out of order. The faces also render easy the association of the transfer member with the supporting member.

What I claim as my invention and desire to secure by Letters Patent is;

1. A loose leaf binder comprising a supporting member having a plurality of impaling projections, and a transfer member having a plurality of transfer projections, the impaling projections and the transfer projections having such shapes in cross section that, when one impaling projection is in abutting relation with one transfer projection, a complete cylinder is formed, the ends of the impaling projections interlocking with the transfer member and the ends of the transfer projections interlocking with

the supporting member to prevent relative lateral movement between the projections.

2. A loose leaf binder comprising a supporting member having a plurality of impaling projections and also having pockets 65 near the bases of said projections, a transfer member having a plurality of transfer projections and also having openings at the bases of the transfer projections for the passage of the impaling projections, the impaling projections and the transfer projections having such shapes in cross section that, when the impaling projection is in abutting relation with one transfer projection, a complete cylinder is formed and the 70 ends of the transfer projections resting in the pockets of the supporting member, and a retaining member coöperating with those portions of the impaling projections passed through the openings of the transfer member.

3. A loose leaf binder comprising a supporting member having a pair of parallel impaling projections, each having a flattened face and a curved face, the opposed faces of the projections being of the same form, said supporting member also having pockets near the bases of the impaling projections, and a transfer member provided with a pair of parallel transfer projections, 85 each having a flattened face and a curved face, the opposed faces of the two transfer projections being alike but different from the opposed faces of the impaling projections, those projections having the flat faces 95 opposed being farther from each other than those having the curved faces opposed, so each pair of projections will hold leaves against sidewise movement thereon, the ends of the transfer projections extending into 100 the pockets of the supporting member.

4. A loose leaf binder comprising a supporting member having a pair of parallel impaling projections formed with flat longitudinal faces, and a transfer member having a pair of parallel transfer projections formed with flat longitudinal faces coöperating with the longitudinal faces of the impaling projections, the ends of the transfer projections interlocking with the supporting member and the ends of the impaling projections interlocking with the transfer member to prevent relative sidewise movement of the supporting and the transfer member.
